UNITED STATES PATENT OFFICE.

DAVID M. PEASE, OF CONCORD, OHIO.

IMPROVEMENT IN CHURN-COVERS.

Specification forming part of Letters Patent No. **150,782**, dated May 12, 1874; application filed May 10, 1873.

To all whom it may concern:

Be it known that I, DAVID M. PEASE, of Concord, in the county of Lake and State of Ohio, have invented a new and Improved Churn-Cover, of which the following is a specification:

In the accompanying drawing, Figure 1 represents a vertical section of the churn-cover on the line xx , Fig. 2; and Fig. 2 a top view of the same.

Similar letters of reference indicate corresponding parts.

The object of my invention is to provide, for the use of farmers and dairymen, an improved churn-cover and guard, which prevents the disagreeable spattering or running over of the cream in churning, and the soiling of the floor and dresses incidental to it.

The invention will first be fully described, and then pointed out in the claim.

A in the drawing represents the upper part of a churn; B, the churn-cover; and C the guard fitted into it. The cover B has a horizontal flange, a , that extends over and rests upon the edge of the churn-body A. In turning back, the cover is loosened, and can be

easily taken off from the churn. The cup-shaped dasher-guard C is placed with its slightly-conical end l in a corresponding recess of the upper side of cover B. Apertures f and f' of cover B and guard C are placed centrally through them, and taper slightly upward to fit closely to the dasher-handle, and prevent as much as possible the passing up of the cream. The conical end l of guard C fits, on turning, firmly and tightly into the cover B, and the bowl of guard C intercepts the particles of cream spattered around by the motion of the dasher, and avoids thereby the soiling of the floor, carpet, and dress.

Having thus described my invention, I claim as new and desire to secure by Letters Patent—

A churn-cover, B, locked on its seat by means of a set-screw or spring and provided with a flaring cup, C, to receive a dasher-rod, as and for the purpose described.

DAVID M. PEASE.
